UNITED STATES PATENT OFFICE.

THOMAS LAUAFATTE GREIF AND BURNICE NEWTON LUSBY, OF ELIZABETHTOWN,
KENTUCKY.

HYDRANT-REPAIRING TOOL.

1,163,232.

Specification of Letters Patent.

Patented Dec. 7, 1915.

Application filed March 2, 1915. Serial No. 11,617.

To all whom it may concern:

Be it known that we, THOMAS L. GREIF and BURNICE N. LUSBY, citizens of the United States, residing at Elizabethtown, in the county of Hardin and State of Kentucky, have invented certain new and useful Improvements in Hydrant-Repairing Tools, of which the following is a specification.

Our invention relates to a tool for use in repairing hydrants, by grinding the valve seats thereof.

An important object of the invention is to provide a tool of the above mentioned character which is simple in construction, inexpensive to manufacture, convenient in use, and formed of few and simple parts which may be readily separated and assembled.

A further object of the invention is to provide a tool of the above mentioned character, having means for connecting the reamer directly to the rotatable rod or to a coupling adapted to be secured to the rod and carrying a guide sleeve, whereby the tool may be used in hydrants having casings of different diameters.

Other objects and advantages of the invention will be apparent during the course of the following description.

In the accompanying drawings forming a part of this specification and in which like numerals are employed to designate like parts throughout the same, Figure 1 is a side elevation of all the elements included in our tool, showing the same in a position to be assembled, Fig. 2 is a central longitudinal sectional view through the elements assembled, and, Fig. 3 is a side elevation of the tool, showing it arranged within the hydrant casing in a position to engage with the valve seat of the hydrant.

In the drawings, wherein for the purpose of illustration is shown a preferred embodiment of our invention, the numeral 5 designates a rotatable rod or body portion, to the upper end of which is secured, as shown in Fig. 1, a handle 6 for turning it, while in Fig. 3 a crank brace 7 is secured thereto. It is to be understood that any suitable means may be employed to turn the rod 5. Rotatably and longitudinally movably mounted upon the rod 5 is a guide sleeve or cap 8, adapted to fit over the top of the hydrant casing 9, and carrying winged clamping bolts 10 to engage therewith, as shown.

The forward or lower end of the rod 5 is provided with a screw-threaded portion 11, to the end of which is secured the reduced screw-threaded portion or trunnion 12.

The numeral 13 designates a coupling, having a tubular portion 14, internally screw-threaded for engagement with the screw-threaded portion 11 and detachable therefrom. The reduced screw-threaded portion or trunnion 12 is adapted to extend within the opening of the tubular portion 14, as shown. The coupling 13 is provided at its forward end with an enlarged head 15, carrying a flange 16 and forwardly of this flange an enlarged screw-threaded portion 17, as shown. This screw-threaded portion carries a reduced screw-threaded portion or trunnion 18, as shown.

The numeral 19 designates a reamer, having a central screw-threaded opening to receive either of the screw-threaded extensions or trunnions 12 and 18, having the same diameter. In Fig. 2, we have shown the reamer 19 as arranged upon the screw-threaded trunnion 18.

The numeral 20 designates a guide sleeve, provided near its rear end with internal screw-threads 21, to engage with the screw-threads of the enlarged extension 17, as shown. The guide sleeve 20 has its rear end engaging the flange 16 and is provided internally with an annular shoulder 22 engaging with the edge of the reamer 19, as shown.

In the use of the tool, the guide casing or cap 8 is secured to the upper end of the casing 9, and the rod 5 moved downwardly within the casing, bringing the guide sleeve 20 over and about a tubular valve seat 23, vertically arranged within the lower end of the casing 9. The guide sleeve 20 fitting about the tubular valve 23 holds the reamer 19 upon the upper end thereof, which is to be cut or ground. Upon rotating the rod 5, it is obvious that the reamer will cut or grind the upper end of the valve seat. Instead of having the cutting surface of the reamer arranged horizontal the same may be inclined for grinding conical valve seats.

When the tool is used in connection with small hydrants, the casings of which are not large enough to receive the guide sleeve 20, this guide sleeve is removed from the coupling 13, and the reamer 19 removed from the 110

screw-threaded trunnion 18. The coupling 13 is now removed from the rod 5 and the reamer placed upon the trunnion 12. The rod carrying the reamer directly secured thereon is now passed through the casing of the hydrant and placed in engagement with the valve seat to be ground, which is effected by rotating the rod. If desired the rod 5 may be extensible and for this purpose it 10 may be formed in sections, connected by detachable couplings.

It is to be understood that the form of our invention herewith shown and described is to be taken as a preferred example of the 15 same, and that various changes in the shape, size, and arrangement of parts may be resorted to within the scope of the appended claims without departing from the spirit of the invention.

20 Having thus described the invention, we claim:

1. A tool of the character described, comprising a rod provided at its forward end with screw-threads and a reduced screw-threaded trunnion, a coupling embodying a 25 tubular portion internally screw-threaded

for engagement with the screw-threads of the rod and provided at its forward end with a reduced screw-threaded trunnion, a guide member carried by the coupling, and 30 a reamer adapted for engagement with either of the screw-threaded trunnions.

2. A tool of the character described, comprising a rod provided at its forward end with screw-threads and a reduced screw-threaded trunnion, a coupling embodying a tubular portion internally screw-threaded for engagement with the screw threads of the rod and provided at its forward end with a reduced screw-threaded trunnion, a 40 guide sleeve having screw-threaded engagement with the forward end of the coupling and surrounding the trunnion thereof, and a reamer adapted for engagement with either of the screw-threaded trunnions.

45 In testimony whereof we affix our signatures in presence of two witnesses.

THOMAS LAUAFATTE GREIF.
BURNICE NEWTON LUSBY.
